LIGHTING SYSTEM

Howard D. Werts, La Salle, Ill.

Application January 24, 1941, Serial No. 375,851

1 Claim. (Cl. 171—97)

My invention relates to lighting systems for motor vehicles and has as one of the principal objects thereof the provision of a lighting system wired in a manner that when one or more of the lights of the vehicle are extinguished due to accidental cause, for instance, short circuiting, defective wiring and/or burnt out bulbs, a sufficient number of lights will remain illuminated in order that the vehicle may be driven over the highway to a suitable locality where the defective portion of the system may be inspected and repaired.

Another object of my invention is to provide a system of the above described character wherein the lights on one side of the vehicle are disposed in a circuit independent of the lights on the other side.

A further object of my invention is to provide a system of the above described character wherein electrically operated accessories are disposed in a circuit independent of the light circuit.

An important object of my invention is to provide a system of the above described character which is extremely simple and efficient in operation and which lends itself to economical installation.

Other objects and advantages will be apparent from the following description, appended claims and annexed drawing.

As diagrammatically illustrated in the single figure of the drawing, I provide a plurality of motor vehicle light sources comprising right front, right rear, left front and left rear lights 3, 4, 5 and 6 respectively. The right and left front lights 3 and 5 constitute a pair of head lights 7 while the right and left rear lights 4 and 6 constitute a pair of tail lights 8. The right front and rear lights 3 and 4 and the left front and rear lights 5 and 6 are connected, by circuits A and B respectively, to the positive terminal of a battery 9, the latter having its negative terminal grounded as at 10.

Inasmuch as the circuits A and B are identical, a detail description of circuit A will suffice, it being understood that the reference characters indicative of the wiring and associated parts of circuit A are provided with exponents "a" to indicate like wiring and parts of circuit B.

The head and tail lights are equipped with electric light bulbs 11 and 12 respectively and with the head lights each provided with a parking bulb 13. Each of the bulbs 11 is equipped with bright and dimmer or high and low projecting beam filaments 15 and 16 respectively and with said filaments 15 and 16 having a com-

mon terminal 17 which together with one terminal 18 of each of the bulbs 12 and 13 is grounded as at G to effect connection with the negative of the battery 9.

5 The filaments 15 and 16 have independent terminals 19 and 20 respectively which, in common with the other terminals 21 and 22 of the bulbs 12 and 13 respectively, are connected to the positive terminal of the battery 9 by the hereinafter described circuits A and B.

As illustrated in the drawing, I provide a switch 23 having a casing 24 of insulating material and which is of a circular configuration in plan and formed with a marginal portion 25, the latter having opposite sides each provided with a ternary of spaced contact members 26, 27 and 28 respectively. The casing 24, adjacent each ternary is formed with a lateral projection 29 provided with a similar ternary of spaced contact members 30, 31 and 32 respectively and with said latter contact members arranged for connection to the contact members 26, 27 and 28 respectively and thus form connectable pairs of contact members for a purpose hereinafter set forth.

Centrally and rotatably mounted within the casing 24 is a bar 33 of insulating material, said bar having fixed to each of its ends a substantially V-shaped contact element 34, the latter being formed with a pair of contact arms 35 and 36 respectively and with the arm 35 adapted for selective engagement with a connectable pair of the aforementioned contact members.

Each of the arms 36 of the elements 34 engages one of a pair of spaced contact plates 37, carried by the marginal portion 25, when the arms 35 are disposed in engagement with the hereinbefore described contact members. The contact members 26, 27 and 28 are connected by 30 means of wires 38, 39 and 40 to one end of a wire 41, the latter having its opposite end connected to the terminal 21 of the bulb 12. The contacts 30, 31 and 32 are connected to the terminals 19, 20 and 22 of the bulbs 11 and 13 by 35 means of wires 42, 43 and 44 respectively. The plate 37 is connected to the positive terminal of the battery by means of a lead 45, the latter having interposed therein a fuse 46. As illustrated in the drawing, an electrical accessory 47 is connected to the positive terminal of the battery by means of a lead 48 having a fuse 49 interposed therein and with said accessory grounded as at 50 for connection to the negative terminal of the battery.

55 The bar 33 is fixed to the lower end of a shaft

50', the latter extending upwardly through the steering column (not shown) of a motor vehicle for rotation by the operator to control the lighting system.

In operation, when it is desired to illuminate the tail lights 12 and the bright filaments 15 of the head lights, the bar 33 is rotated clockwise a sufficient distance to dispose the arms 35 and 36 in engagement with the contact members 26 and 38 and the plate 37, and the contact arms 35a and 36a in connected engagement with the contact members 26a and 38a and the plate 37a. Further clockwise rotation of the bar 33 will enable selective engagement of the arms with the other pairs of contact members and plates to successively illuminate the dimmer filaments and tail lights and the parking bulbs and tail lights. To extinguish the lights, the bar 33 is rotated in the opposite direction a sufficient distance to break the connection between any of the contact members and the plates 37 and 37a as illustrated in the drawing.

From the foregoing, it will be apparent that should any defect occur in one of the circuits when the lights are illuminated, the lights in the other circuit will remain illuminated and thus permit operation of the motor vehicle to a locality wherein the defective circuit may be repaired. It will be noted that the circuits are provided with individual fuses for protecting the respective circuits in case of short circuiting. Furthermore, it will be apparent that the blowing of a fuse in one circuit will in no way effect the condition of the other circuit.

Without further elaboration the foregoing will so fully explain the invention that others may, by applying current knowledge, readily adapt the same for use under various conditions of service. Moreover, it is not indispensable that all the features of the invention be used conjointly since they may be employed advantageously in various combinations and sub-combinations.

It is obvious that the invention is not confined to the herein described use therefor as it

may be utilized for any purpose to which it is adaptable. It is therefore to be understood that the invention is not limited to the specific construction as illustrated and described as the same is only illustrative of the principles of operation, which are capable of extended application in various forms, and that the invention comprehends all construction within the scope of the appended claims.

What I claim is:

In a lighting system for motor vehicles, a pair of headlights one located on the right front side of a vehicle and the other located on the left front side of the vehicle and each including a pair of electric lamps and one having a single filament and the other having a double filament, a pair of tail lights mounted on the rear of the vehicle and each including an electric lamp of a single filament type, means electrically connecting the filaments to an electric ground, an insulated switch mounting including a pair of ground contacts electrically connected to an electric source and the latter electrically connected to the electric ground, groups of contacts mounted on opposite portions of the switch mounting, means electrically connecting the filaments of the headlights to contacts of each group of contacts, means electrically connecting the filaments of the lamps of the tail lights to contacts of the groups of contacts, an elongated rotatable member carried by said switch mounting, and a pair of L-shaped contacts secured to said member adjacent the ends of the latter and movable thereby to bridge the contacts of the groups of contacts in pairs and simultaneously engage the ground contacts for illuminating the lamps of the tail lights with either of the lamps of the headlights and whereby the headlights and tail lights at either side of the vehicle may be illuminated should either of the lamps of the headlights or tail lamps at the other side of the vehicle burn out.

HOWARD D. WERTS.
